Atty.

UNITED STATES PATENT OFFICE.

HENRY LOBDELL, OF TROY, NEW YORK.

CURTAIN-STICK.

SPECIFICATION forming part of Letters Patent No. 292,332, dated January 22, 1884.

Application filed October 23, 1883. (No model.)

To all whom it may concern:

Be it known that I, HENRY LOBDELL, a resident of the city of Troy, in the county of Rensselaer and State of New York, have invented 5 certain new and useful Improvements in Curtain-Sticks; and I do hereby declare that the following is a full, clear, and exact description of the invention, that will enable others skilled in the art to which it appertains to make and 10 to use the same, reference being had to the accompanying drawings, and to the letters of reference marked thereon, which form a part of this specification.

Similar letters refer to similar parts in the 15 several figures therein.

My invention relates to improvements in curtain-sticks; and it consists in providing the sticks with fasteners ranged in a row extending longitudinally of the stick, each fastener 20 having a point or points projecting from the stick, and bent to form an angle with the body of the fastener, which is inserted in the stick, adapted to receive and secure a curtain upon the stick.

25 My invention is intended as an improvement upon the invention described and claimed in Letters Patent No. 286,027, issued to me October 2, 1883, for improvements in curtain-rollers.

30 The object of my invention is to provide a curtain-stick upon which a curtain may be quickly and easily fastened without driving the fasteners and released from the stick without drawing the fasteners therefrom.

35 Figure 1 is a plan view of a portion of a curtain stick or roller provided with my improved fasteners. Fig. 2 is a cross-section taken at the broken line *a b* in Fig. 1. Fig. 3 is a cross-section taken at the broken line *c d* in Fig. 1. 40 Fig. 4 is a cross-section, showing a modified form. Fig. 5 is a plan view of my fastener before it is bent. Fig. 6 is a cross-section, showing the application of my improved fastener to a spring-roller. Fig. 7 is a cross-section, showing 45 another modified form. Fig. 8 is a plan view of a double-pointed fastener. Fig. 9 is a cross-section, showing the method of attaching the curtain.

50 A represents a curtain-stick, which may be a roller, pole, or slat.

C is the fastener by which the curtain P is

fastened to the stick. The stick is rabbeted on one side to form the depression or groove B. The stick is prepared as follows: Straight pointed fasteners like C (shown in Fig. 5) are 55 driven through the stick at suitable intervals in a straight line extending longitudinally of the stick, and the projecting points bent down to about a right angle, to occupy a position tangential to the stick, as shown in Fig. 2. When 60 it is desired to attach a curtain to the stick, the fasteners are all arranged so that the pointed ends all point in the same direction, extending across the depression B at right angles to a line drawn lengthwise of the stick. One end 65 of the curtain is then pressed against the points, which are caused to pierce the same, as shown in Fig. 9. The fasteners are then given one-quarter of a revolution in the stick, which brings them into the position relatively to the 70 stick shown in Figs. 1 and 3 by C', by which the curtain is held securely against the stick, the points of the fasteners lying in the depression B in the stick, which should be of sufficient depth to prevent the projection of the 75 points above the general surface of the stick. The points may be turned all in one direction, or some one way and some the other, as shown by C' C'' C''. By turning the points in different directions the curtain is prevented from 80 being pulled off the points by any strain longitudinally of the stick. E represents a stop, which projects very slightly above the surface of the stick in the depression B, the object of which is to prevent the point C from turning 85 until it is lifted over the stop, and thus facilitate the insertion of the points in the curtain. For example, the point C at one end of the stick is inserted in the curtain, and the latter drawn taut in front of the next point, which is then 90 inserted, and so on until all the points are inserted. The stop E prevents the point C from turning around and releasing the curtain, while the latter is drawn taut to insert the other points. Only one stop is necessary, and is to 95 be located at one end of the stick.

My improved fasteners may be applied to a spring-roller, as shown in Fig. 6. Spring-rollers have the hollow S to receive the spring, and the fastener is forced through the stick at 100 one side of the spring, as shown by the solid lines. When the curtain is affixed, the point

of the fastener projects upward from the stick, but when turned into line with the roller drops into the depression B, the same as before described.

5. Instead of forcing the fasteners through the roller from the outside, it may be shorter and forced through the shell from the hollow within, as shown by the dotted lines.

Instead of providing the fasteners with the head H and driving them through the stick and afterward bending down the points, the fasteners may be made shorter or without heads, and first bent and then inserted blunt end first in the stick, as shown by dotted lines 15 in Fig. 3.

Instead of a single-pointed fastener, one may be used with two points, and formed by doubling a wire upon itself, as shown in Figs. 4 and 8. The points are inserted in the curtain 20 while lying together, and then turned around, and one of the points bent over, so as to lie upon the curtain and point in the opposite direction from the other, as shown by the points D in Fig. 1, in which case one fastener alone 25 will hold the curtain from slipping in either direction longitudinally of the stick.

The double-pointed fastener may be made shorter than the single-pointed, as shown at G in Fig. 7, and the curtain may be fixed upon the points before they are bent down, after 30 which they may be bent down into the depression B—one in one direction, and one in the other, as shown at D in Fig. 1. In this case

the depression B may have a shoulder on both sides, as shown by the assistance of the dotted lines in Fig. 7.

By the term "curtain-stick" I intend to include curtain rollers, poles, and slats.

What I claim as new, and desire to secure by Letters Patent, is—

1. A curtain-stick provided with a row of projecting fasteners ranged longitudinally of said stick, and bent to project tangentially from said stick, substantially as and for the purposes set forth.

2. A curtain-stick provided with a row of fasteners ranged longitudinally of said stick, and having angular projections adapted to swing from a right angular into a parallel line of direction relatively to the general line of direction of the stick, substantially as described, and for the purposes set forth.

3. A curtain-stick provided with a row of double-pointed fasteners ranged longitudinally of said stick, having the points projecting 55 therefrom, and the double points adapted to pierce a curtain together and afterward be separated and bent down upon the curtain, substantially as and for the purposes set forth.

In testimony whereof I have hereunto set 60 my hand this 20th day of October, 1883.

HENRY LORDELL.
